ALARM INSTALLATION WITH CENTRAL POWER SUPPLY

Curt Fredrik Ahlberg, Appelviken, and Sten Åke Nilsson, Nockeby, Sweden, assignors to Telefonaktiebolaget L. M. Ericsson, Stockholm, Sweden, a company of Sweden

Application October 20, 1941, Serial No. 415,806
In Sweden October 25, 1940

5 Claims. (Cl. 177—369)

The present invention relates to alarm systems with a central alarm station and local alarm installations.

Fire and burglar alarm systems are known in which alarm loops containing normally closed alarm contacts are extended to the premises to be protected. These line loops are put under so-called supervisory current control and alarm is indicated on a central board when break-down occurs in the line. Such break-down occurs at an alarm contact when it is put out of operation by heat or mechanical influence, but a break-down may occur naturally in case of damage to the line. In the latter case a false alarm indication is given on the central board. The risk of false alarms is considerably reduced if the system is arranged with two parallel line loops with two-point alarm contacts whereby it is necessary for the alarm operation that a break-down occurs in both loop circuits.

Such systems are very suitable for the supervision of premises forming an entire building, for instance a factory or a commercial building. If it is a question of the protection of several localities at some distance from each other or of a locality which for some reason is situated away from the centre of supervision (for instance a police or fire station) the lines become very expensive if they are to be built exclusively for that purpose. A considerable reduction in the line cost may be gained if already existing lines are used and this reduction is obtained in many places where one or several communal fire telegraph loops are already available which are used for the transmission of alarm signals from automatic fire alarm plants. However, in such cases battery fed repeaters with code signal mechanism should be inserted between the alarm loops and the fire telegraph loop. This will reduce the line costs but, on the other hand, the repeater is added which renders this method uneconomical for small plants having only one or a small number of supervisory loops. Another drawback is that only a limited number of premises to be protected may be connected to one and the same fire telegraph loop, the impulse code not allowing for variations beyond a certain limit.

The present invention is intended for the use of spare lines in an existing telephone network for transmission of alarm signals from a number of dispersed places of protection to a supervisory centre. A system according to the invention must fulfill certain conditions. Firstly, the line (central line) between the single or two-wire alarm loop itself and the central board must consist at

the most of one two-wire telephone line. Secondly, the system must allow unintentional intermittent or lengthy break-downs, short-circuits, grounding or the like on the central line without a false alarm being indicated at the supervisory centre. Thirdly, all such faults as well as faults of the same kind in the alarm loops themselves must be indicated at the centre in such a way as to enable determination of whether the faults have occurred in the central line or in the alarm loop.

The invention will now be described in greater detail with reference to the accompanying drawing, the figure of which shows an embodiment of a system which fulfills the aforesaid requirements.

Characteristic of the system is that the local alarm loop and the central line are connected to each other without having recourse to movable elements and without any local power supply being used for transmission of signals from the alarm loop to the supervisory centre. Further the central line and the alarm loop are automatically tested from the centre. In the embodiment shown the central line is tested on the occasion of an alarm by means of alternating current and a relay sensitive to alternating current whilst the alarm loop is tested with direct current and a relay sensitive to direct current.

On the drawing B_1 , B_2 and B_3 represent direct current supplies and O_1 and O_2 alternating current supplies. AS_1 and AS_2 are two local alarm loops, the former of which is a single wire and the latter a double wire. Between the alarm loops and the central line CL an impedance network is inserted consisting of condenser C_2 , transformer TR and resistances r_2 and r_3 . For every central line CL the central station is equipped with the following devices:

40 A line compensation resistance r_1 ;
Relays R_1 , R_2 and R_3 which are normally connected in series with line CL ;

Relays R_4 and R_5 which on break-down in the direct current circuit over CL , TR , AS_1 and AS_2 are connected to central line CL and test the latter, whereby relay R_4 , being shunted across condenser C_1 , is actuated by direct current but not by alternating current and relay R_5 is energized both by direct current and alternating current;

45 An alarm relay R_6 and a fault relay R_7 ;
Signal lamp KL for short-circuiting, signal lamps ATL , KCL , CLL for different central line breaks and signal lamp ASL for a single-wire alarm loop break;

50 A resetting switch A ; and

A battery switch BO.

The central line is moreover equipped with signal lamps SFL , LL and AL , common to a number of central lines, and with earth fault lamps JF_1 and JF_2 . There are also earth fault relays JR_1 and JR_2 for both batteries B_1 and B_2 as well as a converter start relay SR which, in known manner, is slow-acting.

The operation of the system will now be described.

By intact central line CL and alarm loops AS_1 and AS_2 , a supervisory current flows in a circuit 11 from battery B_1 through relays R_1 , R_2 and R_3 which with resistance r_1 is adjusted to a determined value. Relays R_1 and R_2 which formerly, by pushing of the button A and closing the contacts 14, 15 have been energized over a circuit 12 with relatively high current keep the armatures attracted for the lower supervisory current, whilst R_3 is not able to attract its armature for the supervisory current. This condition is shown in the drawing.

If now short-circuiting or a sufficiently powerful leakage follows between the two branches of the central line CL , relay R_3 is energized by a higher current and operates its armature 16 and lights the lamps KL and SFL over the circuits 17, 18.

In the case of a single-wire break-down in the alarm loop AS_2 , the relay R_2 releases its armature 21 owing to the current decrease whereby lamps ASL and LL are illuminated over the circuits 22, 23.

If a double-wire break in the loop AS_2 or a break-down in loop AS_1 occurs, the relays R_1 and R_2 release their armature with the following result:

Relay SR is actuated over the contact 25 and closing of the contacts of relay SR closes a circuit of a starting device (not shown) for the converters. Relays R_4 and R_5 are, over contact 26, connected to the central line CL in a circuit over B_1 , O_1 , r_1 , one of the branches of CL , condenser C_2 and the other branch of CL . The circuit is set under both direct and alternating voltage but alternating current alone can pass through the relays, the condenser C_2 blocking the direct current. Relay R_5 operates but not relay R_4 , whereby relay R_6 is energized over contact 27 and the alarm lamps AL and ATL are illuminated over contacts 28 and 29.

On break-down in central line CL the same result will first happen as in the above case, but neither relay R_4 nor R_5 will now be actuated on de-magnetization of relays R_1 and R_2 . A circuit is closed over the contact 31 through the lower winding of the relay R_7 and the lamp KCL . The two lamps LL and CLL are illuminated over contacts 32 and 33 and the lamp SFL in a circuit over the contact 34.

After all above-mentioned circuit alterations the relays may be reset to normal position by pushing key A . In case of a complete break-down both in the loop AS and in the line CL , the combined direct and alternating voltage remains on the central line. Should the breaks be of short duration the relay R_4 is actuated on removal of the break whereby relays R_1 and R_2 operate in a circuit from battery B_2 over contact 35 and are again set under supervisory current. When the relay R_1 attracts its armature, relays R_4 and R_5 release their armatures and the converter stops but that one of the relays R_6 and R_7 which has been actuated retains its armature in circuits 36, 37 causing the existing signal ATL or CLL to re-

main. On the other hand signal SFL or KCL does not remain in this case.

After a short-circuit break-down of short duration the relay R_3 retains its armature due to the supervisory current being able to magnetize the relay sufficiently to lock it but not enough for attraction.

After a short single-wire break-down in the loop AS_2 , the relay R_2 is for the same reason unable to attract its armature.

Thus both signals KL and ASL remain operative after faults of short duration.

On a leakage to earth from one of the two branches of central line CL or from some alarm loop, the relay JR_1 operates in a circuit from earth to battery B_3 , which is connected to earth and the lamp JF_1 is illuminated over contact 41. If the leakage is not located in the lower branch of the central line, the relay R_3 also attracts its armature and the lamps KL and SFL are illuminated. Should the leakage disappear, the signals KL and SFL , however, remain whilst the lamp JF_1 is extinguished, the relay R_3 as above still being actuated.

Since all lines are connected in parallel to the battery B_1 , the relay JR_1 will be set under the total leakage current from these lines to earth. It might therefore happen that the relay JR_1 attracts its armature without the leakage in every line having reached an inadmissible value. In that event, it is convenient to switch the faulty lines to battery B_2 and converter O_2 through the switch BO . The earth fault relay JR_2 may thereby be constructed for a higher energizing current than the relay JR_1 so that it does not attract its armature until a direct connection to earth has occurred on a line.

It will be seen from the above firstly that an alarm (lamp AL , bell AK) is not emitted by lasting or intermittent faults on the central line; secondly, that faults which prevent the transmission of alarm signals are indicated as major faults by the lamp SFL ; thirdly, that faults which do not prevent the transmission of alarm signals are indicated as minor faults by the lamp LL ; fourthly, that faults of short duration are signalled by means of continuing signals, thus calling for examination of the lines; and finally, that faults of short duration do not interrupt the emission of ultimate alarm signals since at least the relay R_1 , and possibly also the relay R_2 , upon the removal of an arbitrary fault, attracts its armature, even should the reset switch not have been previously operated.

On a complete break-down in the alarm loops which is of so short a duration that the loops are closed when relays R_4 and R_5 become connected for testing and thus both should be actuated, as an alarm signal may be transmitted, the resistance r_2 may be replaced by a relay (not shown) which, its armature having been moved by hand against the magneto core over its own make contact, become energized and thiereupon retains the armature in attracted position. This relay may be adjusted so that its release time becomes sufficiently short to ensure its release upon even the shortest loop break-down occurring. Once released it cannot be actuated since its make contact is now opened, wherefore, even should the alarm contact in the loop be closed, an alarm signal is emitted at the central board.

In the example of an alarm system according to the invention and shown in the drawing, the branches emanating from the central station of line CL in the local plant which lies to the right

on the drawing are connected to each other a condenser C_2 , whereby these two branches will form a single-wire loop circuit for alternating current. This loop circuit is then electrically connected at the local plant to loop circuits AS_1 and AS_2 . This electrical connection is constituted by the windings on transformer TR and of resistance r_2, r_3 . Alarm loops AS_1, AS_2 may consequently be supervised or tested from the central station by the aid of direct current. Naturally, other arrangements than those given in this example may exist in the local plant without affecting the principle of the invention. Consequently, the two central line branches may be connected to each other over a choke coil which thus replaces condenser C_2 , whereby the local alarm circuits become connected to this coil from the central board emanating loop circuit for direct current over a condenser and resistance. The local loop circuits are thereby connected in parallel with the choke coil and may be supervised from the central station by means of alternating current.

According to a different embodiment, the central line branches may be connected to each other over the primary winding of a transformer and the local loop circuits connected to the secondary winding of the transformer. According to still another modification, the two central line branches may be connected to each other over an ohmic resistance, whereby the local alarm circuits in series with other ohmic resistances are connected in parallel to the first-mentioned ohmic resistance.

In the embodiment described, a test made over the central line is carried out when an indication has taken place. Under certain circumstances it may prove advantageous to undertake further tests.

We claim:

1. An alarm system comprising a central alarm station, sources of alternating and direct current in said station, local alarm loops with two-wire lines outside the station, a central two-wire line extending from said station and connected to said local alarm loops and forming a central loop

circuit, a blocking device for the direct current in said loop circuit at the connection between the central line and the local alarm loops, a relay device in said central station connected with said central line and operable by said direct current, a second relay device operable by the alternating current and connected between said central line and said alternating current source after operation of the first relay device, signal circuits controlled by said relay devices, and signal devices in said signal circuits for indicating whether changes in the line conditions have taken place in the central loop circuit or in the local alarm loops.

5 15 2. An alarm system as claimed in claim 1 in which the blocking device is constituted by a condenser and in which the local alarm loops are in series with a resistance connected in parallel with said condenser.

20 25 3. An alarm system as claimed in claim 1 in which the two wires of the central loop circuit at the connection to the local alarm loops are connected to each other over the primary winding of a transformer, the local alarm loops being connected to the secondary winding of the transformer.

30 35 4. An alarm system as claimed in claim 1 in which a supervisory device at the central alarm station is so arranged that a supervisory circuit for direct current is closed from said device and that on change of current in said supervisory circuit the alternating current becomes connected to the central two-wire line.

5 40 45 5. An alarm system as claimed in claim 1 in which the first mentioned relay device includes relays through which supervisory current is closed from the direct current source to the central two-wire line, certain of said relays being so constructed that the normal supervisory current is unable to energize such relay, but if such relay is energized by a higher energizing current, the normal supervisory current is sufficient to maintain such relay energized and its armature attracted.
